WRAPPING MACHINE

Michael J. Milmoe, Glen Ellyn, Ill., assignor to
 F. B. Redington Co., Chicago, Ill., a corporation
 of Illinois

Application May 25, 1933, Serial No. 672,840

31 Claims. (Cl. 93—2)

The present invention relates to a wrapping machine for wrapping cylindrical containers or articles. Obviously the invention can be used to wrap articles such as circular cakes of soap or 5 the like, whether or not they are in a container. The main purpose of this invention is to provide a wrapper for an article or container in which the wrapper which is in the form of a flat rectangular sheet of paper may be wrapped about the 10 article to form a tube with the ends of the tube extending beyond the article and then closing the ends of the tube by suitable mechanism which quickly folds the extending portions of the tube in such a manner that the portions after 15 they are folded interlock to prevent the unfolding thereof.

One object of this invention is to properly center the wrapper with respect to the article being wrapped in order that portions of the tube 20 formed, in first folding the wrapper about the article, will extend equally beyond both ends of the article and for a reason which will appear hereinafter as the description of the invention proceeds.

Another object of this invention is to provide 25 a wrapper for a container of the class described in which a certain amount of economy can be effected due to a saving of the wrapping material. Also an economy is effected by using a square 30 blank which can be cut by the machine into suitable rectangular blanks for each individual container and while the machine is in operation. This mechanism for cutting the blanks into sheets is well known in the art to which this invention pertains and is not shown or described 35 herein. It may be assumed that the sheets are fed to the machine by hand from a suitable stack as far as the operation of the machine is concerned, except that the wrapping material must 40 be fed in timed relation to the operation of the other parts. However, I am not claiming in this application any invention in the means for forming or feeding the wrappers and the feeding means for the wrappers is only diagrammatically 45 shown in the drawings.

Another object of this invention is to provide a compact means for wrapping the container and for forming the tubular interlocking folds at 50 the ends thereof.

Another object of this invention resides in the means for producing the interlocking folds by a simple compound movement of a single unit which is rugged and can operate at a high rate 55 of speed. Furthermore, the forming of the tubu-

lar ends occurs at only one position of the article in its path of travel with the exception of the operation of the creasing devices which merely supplement the action of the fold forming mechanism.

Another object of this invention will appear hereinafter as the description thereof proceeds, the novel features, arrangements, and combinations being clearly set forth in the specification and claims.

In the drawings:

Fig. 1 is a front elevational view of the machine embodying my invention;

Fig. 2 is a side elevational view looking from the right in Fig. 1;

Fig. 25 is a partial side view of the machine showing more particularly parts of the end folding mechanism, and Fig. 26 is a perspective view showing more particularly parts of the end folding mechanism.

Referring particularly to Figs. 1, 2, 3, and 4, it will be noted that the reference character 30 represents the base frame of the machine, and this may be constructed in any suitable manner for rigidity, but preferably comprises a flat upstanding web portion 31 with rearwardly extending web portions 32 extending rearwardly from all four sides of the web 31. This base frame supports the main portions of the machine and on this frame there is mounted a bracket 33 which supports part of the operating mechanism and a bracket 35 which rotatably supports the shaft 36 which has the turret 37 secured thereto. These brackets are best illustrated in Fig. 2, and are carried by the base frame 30. The turret comprises two disk-like members arranged in spaced parallel relation with each other. These disk members are indicated by the reference character 38 and the spacing thereof is best illustrated in Fig. 4. The disks have aligned pockets 39 for receiving the articles or package which are of a circular shape and flat at both ends. The package is indicated by the reference character 40, and the container is indicated by the reference character 41. In order to hold either the package or the container in the turret, I provide the retainers 42, pairs of which are carried by the pivoted arm 43 arranged between the disks 38 and pivoted on a pin 44 which extends into both disks 38. Springs 45 attached at 46 and 47 to the retainers 42 and disks 38 respectively, normally tend to rotate the retainers 42 in a counter clockwise direction as viewed in Fig. 1, but a means is provided for moving these retainers against the action of the springs when so desired.

I shall designate the various positions for the pockets of the turret as A, B, C, D, E, F, and G. At the position A, the container with the wrapper partially wrapped thereabout is moved into the pocket at that position, and carried to the position B, and in passing from A to B, the entire tubular wrapper is formed about the container. It then moves to the position C where the ends of the tubular wrapper are closed. Next to the position D where the folds of the wrapper are creased, and then through the positions E and F to the position G, where the completed package is ejected from the turret and caused to move into the trough 48.

Before proceeding with a description of the successive steps in the operation of this machine, I wish first to describe the means for operating the retainers 42 against the action of the springs 45 and this means is perhaps best illustrated in Figs. 1, 2, 3, 9 and 15.

The bracket 35 has an extension positioned adjacent to and rearwardly of the rear disk 38, and

this extension carries pivots 50 on which there are pivoted the arms 51 connected by a link 52. Secured to the arms 51 are the projecting releasing members 53 which are adapted to engage the pins 54 projecting from the retainers 42. The arms 51 and link 52 cause the releasing members 53 to move in unison with each other and the releasing members are operated by means of a cam 55 secured to the shaft 56, and a lever 57 which is pivoted at 58 and has a roller 59 engaging the cam 55. The lever 57 is connected to one of the releasing members 53 by means of a link 60 pivoted at 61 to the lever 57 and at 62 to an arm 63 which is rigidly connected to that operating member which is shown at the left in Fig. 15. The cam is so constructed that normally the retainers 53 are out of the path of movement of the pins 54, but after the turret has come to rest, the pins are engaged by the releasing members 53 by a clockwise movement thereof as viewed in Fig. 1 or a counter-clockwise movement as viewed in Fig. 15. This results in releasing the retaining members 42 to permit a container to be moved into a pocket A together with the wrapper therefor, and also to permit the package 40 to be moved into the trough 48 without being retarded by the retaining members which might otherwise tear the wrapper or otherwise interfere with the operation of inserting a container into or removing it from a pocket. This also enables me to have the engaging surface of the retaining members shaped the same as the adjacent surface of the container thereby resulting in a more positive action than would otherwise be possible. At all positions except at the positions A and G, the retainers 42 remain in operative gripping engagement with the container or package.

As will be clear from an inspection of Figs. 2 and 3, the shaft 56 carries a sprocket 64 which is driven by a chain 65 from a sprocket 66 secured to the jack shaft 67 driven by bevel gears 68 and 69 from the main drive shaft 70. The chain 65 is also trained over a sprocket 71 on the shaft 72 which is supported by the brackets 35 and 34. Several parts of the mechanism are driven from the shaft 72 in a manner which will appear as the description proceeds.

One of the parts of the mechanism driven from the shaft 72 is the turret 37. This is accomplished through the intermediary of a Geneva movement, the rotating disk 73 of which is secured to the shaft 72 and the wheel 74 of which is secured to the shaft 36. The operation of the Geneva movement will not be described as it is well understood in the art to which this invention pertains. It is sufficient to state that on each revolution of the shaft 72, the turret is advanced to bring each pocket to its next successive position.

I shall now describe the manner in which the containers are fed into the turret, and the manner in which the wrapper is placed about the container as it is being inserted into the pocket at the position A. This means is best illustrated in Figs. 1, 2, 5, 6, and 7. Located just beneath the pocket at the position A is a table 75 and this table has an opening 76 therein, see Fig. 6, through which the container 41 may be moved upwardly into the pocket at the position A. The containers 41 are moved from a position beneath the table 75 to a position within the pocket at the position A by means of an elevator comprising an arm 77 which has spaced brackets 78 secured thereto at the upper end thereof, the brackets 79 having upwardly projecting pins 80.

The arm 77 is carried by a block 81 which in turn is mounted on the upper end of a shaft 82 slidable in bearings 83 on the bracket 84 secured to the web 31. In order to prevent rotation of the block 81, I provide a U-shaped guide 85 on the web 31 and a roller 86 rotatably mounted on the block 81 is guided within the guide 85 as the shaft 82 moves up and down. In order to move the elevator in a vertical direction, I provide an arm 87 secured to the shaft 88 which in turn is secured to a suitable bearing 89 (see Fig. 2) on the web 31. An operating arm 90 also secured to the shaft 88 has a roller 91 cooperating with a cam groove in the cam 92 which is secured to the shaft 67 and rotates therewith. The arm 87 is connected by a link 87' to the block 81 so that upon rocking of the arm 87, the block 81 is reciprocated in a vertical direction.

A chute 93 U-shaped in cross-section is provided for containers and this is inclined downwardly toward the arm 77 and the endmost one at the right of the chute normally rests against the arm when the arm is in its uppermost position. As the arm moves to its lowermost position, a container moves onto the end of the arm 77 between the brackets 78 as clearly indicated in Fig. 7. The upward movement of the arm 77 carries the container into engagement with a sheet of wrapping paper 94 which rests on the table 75. This sheet of wrapping paper is fed onto the table in any desired manner and in Fig. 2, I have represented diagrammatically a feeding member 95 which engages the sheet of wrapping material 94 and pushes it onto the table 75 after which rollers such as 96 may be used to feed the wrapping material. This part of the mechanism does not form a part of my invention, but should be a mechanism which will accurately feed the wrappers onto the table into a predetermined position so as to insure that the next operations on the wrapper will be proper, and that the package will be properly formed. The sheets of paper may be formed from a continuous web associated with the machine, or may be blanks which are previously formed and fed to the machine in any desired manner. As the paper is moving into position on the table, glue is applied to one edge thereof by the glue applying roller indicated diagrammatically at 97 which picks up glue from a glue trough in any well known or desired manner. This glue applying roller extends through a slot (not shown) in the table and the upper surface thereof is just slightly higher than the surface of the table so that the glue will be properly applied thereto. Means may be provided for pressing the paper into engagement with the glue applying roller as it is fed into position.

Assuming that the paper has been properly fed on the table 75, and located thereon, I shall now proceed to describe the manner in which the container is moved into the pocket at the position A and the wrapper 94 partially wrapped about the same. Positioned above the table 75 and having movement toward and from the surface thereof are pivoted presser members 98 pivoted at 99 to an arm 100 which is secured to a shaft 101 rotatably mounted in a suitable bearing 102, see Fig. 2, in the bracket 35. To the rear of the bracket 35 and secured to the shaft 101 is an arm 103, see Figs. 1 and 3, which is connected by a link 104 to a bell crank, one arm of which is indicated by the reference character 105 and the other arm of which is indicated by the reference character 106, see Figs. 1 and 3. The end of the arm 106

carries a roller 107 engaging within a suitable cam groove in the cam 108. The cam groove is so designed as to periodically rock the bell crank and as a result move the arm 100 up and down by means of the connections just described for a purpose which will appear presently. As will be noted from an inspection of Figs. 5 and 6, the presser members 98 have a limited amount of pivotal movement with respect to the arm 100. The pressure members 98 are provided with slots 109 through which pins 110 on the arm 100 extend. There is a friction means to resist the movement of the presser members 98 with respect to the arm 100 and this means comprises friction washers 111 which surround the pins 110 and are 15 spring pressed against the presser members 98 by springs 112 abutting against the washers 111, and washers 113 surrounding the pins and held in place by cross-pins 114 or any other suitable manner. The presser members have laterally extending portions 115 provided with openings 116 for the reception of the pins 80 when the presser members 98 and laterally extending portions 79 on the brackets 78 are in juxtaposition with respect to each other.

Now as the elevator 77 moves upwardly into the position shown in Fig. 9, the presser members 98 are in a position just contacting with the upper surface of the paper and pressing slightly against the same. The pins 80 pierce the paper 30 and extend through the openings 116. These pins hold the paper in proper juxtaposition with reference to the presser members so that the paper will occupy the proper position until it is inserted in the turret. With some types of paper, 35 the pins are not necessary as the pressure between the presser members 98 is sufficient to hold the paper in proper alignment.

It will be noted from an inspection of Figs. 6 and 7 that the upper surfaces of the laterally extending portions 79 of the bracket 78 are curved substantially to the curvature of the article 41 and extend outwardly a distance sufficient to underlie the outer ends of the paper 94. Therefore, there is a continuous unbroken support for the center 45 portion of the paper as the elevator 77 moves upwardly to bring the article 41 into engagement with the paper so that the paper will immediately start to fold along a line which is substantially in alignment with the cylindrical article 41. If it 50 were not for the extensions 79, the article 41 when moved against the paper might cause a folding of the paper along the peripheral edges of the article and crease the same in a direction opposite to that desired. It is not necessary that the extensions 79 extend inwardly into engagement with the article or in close proximity thereto as the important feature is to have the outer edges thereof contacted by elements which are practically extensions of the surface of the article 60 which first moves into engagement with the paper so that the paper begins to fold in the proper direction as the elevator 77 moves upwardly. Thus in the case where the article to be wrapped is a bottle having a neck which is of reduced size from the body of the bottle, the upper surfaces of the extensions 79 will be substantially continuations of the body portion of the bottle, but one of them, at least will be spaced from the body of the bottle due to the neck portion thereof. 65 With the cylindrical articles such as 41 shown in the drawings, it is possible, of course, to have the members 79 extend from a position closely adjacent the article outwardly a distance sufficient to support the outer free edges of the paper in the 75

manner which is clearly illustrated in the embodiment of the invention shown herein. It is not absolutely necessary that the upper surfaces of the extensions 79 be curved transversely in the manner illustrated in Fig. 6. It is sufficient if at least a line contact with the paper is provided substantially centrally of the article so as to cause the initial breaking of the paper in the proper direction instead of in a direction transversely thereto. This feature improves not only the appearance of the finished package but also insures that the mechanism for folding the protruding ends of the wrapper will function properly when they come into operation as hereinafter set forth.

15 The elevator then continues its upward movement, and the presser members move along with the elevator and container 41 carried thereby in such a manner as to maintain the presser member preferably in continuous contact with the paper. The pivotal movement of presser members 98 with respect to the arm 100 compensates for any slight difference in the speed of movement of the elevator 77 and of the arm 100. The continued upward movement of the elevator 77 carries the container and wrapper 94 into the pocket in the position A, and the sides of the pocket wrap the wrapper partially about the container with the free ends of the wrapper extending downwardly. At the time that the container 30 is moving into the pocket at the position A, the cam 55 becomes operative to move the retainers 42 against the action of the springs 45 so that there is no resistance offered to the movement of the container and wrapper into the pocket. Immediately thereafter, however, the cam 55 becomes inoperative and as a result, the springs 45 move the retainers 42 toward and against the side of the container and hold the container and wrapper in the pocket. The elevator 77 and presser member then descend to their original positions, after the turret has moved, to pick up the next container and wrapper therefor, and move the same in a similar manner in the next succeeding pocket to arrive at the position A. 45 The next step in the process of wrapping the container is to wrap the free extending ends of the wrapper about the container and in overlapping relation with each other with the glued portion which is indicated by the reference character 117 in Figs. 6, 9, and 10, between the overlapping portion of the ends of the wrapper. The means for accomplishing this result is best shown in Figs. 1, 9, 10, and 11. The first operation is to fold the downwardly extending portion of the wrapper 50 which is at the right as the same is viewed in Fig. 1, or in Figs. 9 and 10, and this is accomplished by means of a substantially horizontally movable plate 118 which is carried by the end of a reciprocating support 119 carried by parallel arms 120 pivoted thereto at 121. Arms 120 are secured to the shafts 122 rotatably mounted in suitable bearings 126 on the web 31. The reciprocating movement is imparted to the support 119 by means of an arm 123 secured to the shaft 122 at the left in Fig. 1 which is rocked angularly by the cam 124 secured to the shaft 67 and having a cam groove in which a roller 125 on the end of the arm 123 travels. See particularly Figs. 1 and 2.

70 A pair of rods 127 are slidably mounted in bearings 128 on the support 119, and their movement to the left is limited by the heads 129 on the rods 127, and the opposite ends of the rods carry a presser member 130 between which and the left hand one of the bearing 128 there are

arranged the springs 131 surrounding the rods 127 and abutting respectively against the presser member 130 and bearing member 128. The plate 118 is not rigidly secured to 119 but has openings through which the pins 132 extend, the pins being surrounded by springs 133 abutting against the plate 118 and washer 134 whereby the plate 118 is normally held in the position shown in Fig. 10 but is permitted to yield downwardly at the free end thereof so that when the plate 118 is moving the free end 135 of the wrapper about the container, it will yieldingly press the wrapper against the side of the container and stretch the wrapper about the container.

As the support moves to the left, the plate 15 118 and presser member 130 operate on the free end 135 of the wrapper to move the same into the position shown in Fig. 10. This is accomplished just prior to the movement of the container to the next successive position. In this 20 position of the presser member 130, the springs 131 are compressed and as the turret begins its movement in a clockwise direction to move the container to the next successive position, the springs 131 expand so as to maintain the presser 25 member 130 always against the wrapper to retain the wrapper in place as the turret revolves.

The base frame 30 is provided with an upwardly extending bracket 136 and this bracket carries at its upper end a U-shaped folding member 137 which is shown in cross-section in Fig. 9, and comprises a base portion 138 and an upwardly extending portion 139. Fastened to folding member 137 is a curved extension 140. Extending through the opposite legs of the U-shaped portion 139 is a pin 141 which carries a pivoted folding member 142 spring pressed in a counter-clockwise direction by a spring 143 abutting against the folding member 142 and base portion 138, the rotative movement being limited by 35 a stop 144 engaging a tail-piece 145. In Fig. 10, the folding member 142 is shown in its uppermost position, whereas in Fig. 9, the folding member is shown in its depressed position to which it is moved by the container as the turret 45 carries the container past the folding member. This causes the extending end portion of the wrapper which has the glue 117 thereon to be stretched tightly about the periphery of the container and as the turret continues its movement, the free end portion carrying the glue is brought into overlapping relation with the other end portion and the pressure of the folding member 142 and curved extension 140 causes the overlapping portions to be adhered together. 50 At about the time that the overlapping portions are brought into juxtaposition with respect to each other, the plate 118 and presser member 130 return to an inoperative position to the right of the machine as viewed in Fig. 1.

The partially wrapped container is then carried to position C at which position, the open ends of the container are closed by forming a plurality of folds in overlapping relation with respect to each other at each of the tubular ends. 65 The mechanism for accomplishing this result is best illustrated in Figs. 1, 2, 3, 4, 8, 12 to 14 inclusive, 16 to 18 inclusive, and 21. I shall first describe the operation of the means which forms the plurality of folds, and thereafter, I 70 shall describe the means by which the parts of the folding mechanism are operated. The manner in which the folds are made is perhaps best illustrated by an inspection of Figs. 12 to 14 inclusive and 16 to 18 inclusive. When the con- 75

ainers arrive at the position C, the wrapper is in the form of a tube which embraces the outer periphery of the container and projects beyond the opposite ends thereof. In Fig. 12, I have 5 illustrated the tubular end portion which projects beyond the container by the reference character 146. A shaft 147 is rigidly secured in a bearing 148 in any desired manner and the axis thereof is substantially in alignment with the axis 10 of the container at the position C. Rotatably mounted on this shaft is a sleeve 149 to which there is secured a gear 150 as by screws 151 and to which there is also secured a finger support 152 to which there are pivoted the fingers 153 15 at 154. The fingers 153 have tail-pieces 155 which are notched at 156, and have beveled surfaces at 157. A spring 158 or rubber band surrounds all of the tail-pieces 155 and is arranged within the notches 156 formed therein so as to 20 normally cause the forward ends of the fingers to be thrown to the position shown in Fig. 12. In order to move the fingers against the action of the spring 158, I provide, a sliding clutch element 159 which has a beveled surface cooperating 25 with the beveled surfaces 157 on the tail-pieces 155 so that when the clutch element is shifted to the left, the forward ends of the fingers are thrown inwardly as indicated in Fig. 13. The clutch element carries a grooved collar 160, 30 and a shifting arm 161 secured to a shaft 162 has a roller 163 which engages the groove in the collar 160 so as to enable the clutch element to be shifted while the clutch element is rotating, as well as while the clutch element is not rotating. 35 A segmental gear which will presently be described meshes with the gear 150 to rotate the same in opposite directions, and thereby impart an oscillating movement to the sleeve 149. The clutch element 159 carries a plurality of parallel 40 pins 164 which extend substantially parallel to the axis of the shaft 147 and slidably extend through guide openings in the finger support 152. The bearing 148 as will presently appear is shiftable bodily in a direction parallel to the shaft 147 45 to bring the parts into the position illustrated in Fig. 12 when the partially wrapped container arrives at the position C, and to move the same clear of the path of movement of the extreme ends of the wrapper while the turret is moving 50 so that the projecting end portions of the wrapper will not engage the fingers 153 prior to the arrival of the container at the position C.

Let us consider the action of this folding mechanism independently of the actuating means which is to be described later. The mechanism is first given a bodily movement to the right to bring the parts into the position illustrated in Fig. 12. It is understood that in connection with the description of this mechanism that it applies to the folding mechanism at the left in Fig. 2, and that the same mechanism at the right in Fig. 2 operates in a similar manner except that the movements are somewhat reversed so as to operate on the other end 65 of the container. However, the two mechanisms operate identically as far as the folding is concerned, and the description of one will be sufficient to describe both folding mechanisms. As will be noted from an inspection of Fig. 12, the 70 pins 164 are arranged inside of the extending portion 146 and the fingers 153 are arranged outside of the same portion. After the parts arrive at the position indicated in Fig. 12, the clutch element 159 is shifted to the left in the manner previously described, and this move-

ment causes the tail-pieces 155 on the fingers to move outwardly and the fingers to move inwardly to bring portions of the wrapper between adjacent pins 164 in the manner illustrated in Figs. 17 and 18. This produces a series of longitudinally extending folds which I have indicated in Fig. 18 by the reference character 165. When the clutch element 159 moves to the left, it carries with it the pins 164 and retracts them to the position illustrated in Fig. 13, but the retraction 10 does not take place until the folds have been formed to a certain extent, that extent being illustrated in Fig. 18. After the parts arrive at the position shown in Figs. 17 and 18, the fingers 153 continue their movement inwardly 15 to move the folds closer together and to a position substantially centrally of the end of the tubular wrapper. This also narrows the folds and when the parts arrive at substantially the position illustrated in Fig. 13, a rotating movement 20 is imparted to the gear 150 and this in turn causes the fingers 153 to rotate and in doing so, the folds 165 are brought into overlapping relation with each other, with a portion of each fold over a portion of the adjacent fold on one 25 side and under an adjacent fold on the other. This novel arrangement of the folds whereby each at its inner end is arranged so that it in part overlies the adjacent fold on one side and is in part tucked under the adjacent fold on the 30 other side, as will be seen more particularly from an inspection of Fig. 20, is insured by the offset mounting of the pivoted fingers 153. Referring to Fig. 14, it will be seen that the fingers are so disposed that as they are pivoted radially inwardly, their ends will pass near but not through the central axis of the wrapper. As a result the wrapper folds will be struck inwardly along 35 lines which deviate slightly from true radial lines, thereby producing a wrapper end fold having the novel characteristics as shown in Fig. 20. The novel wrapper itself forms the subject matter of my copending application, Serial No. 21,085, filed May 13, 1935, wherein claims to the wrapper article are presented. While the fingers 40 45 50 55 60 65 70 75

53 are being rotated, the bearing member 148 is carried to the right an additional amount until the fingers are substantially against the end of the package as indicated in Fig. 16. The rotating movement of the fingers will tend to crease portions of the folds, and the creasing will practically prevent the folds from unfolding. It will be noted that since the extending portion 146 of the wrapper has a length which is substantially equal to the radius of the end of the container, the folds only extend to the center 166 of the end of the container as indicated in Fig. 20, the ends of the folds being indicated by the reference character 167. In order to properly crease the folds, however, I provide an additional creasing mechanism to be hereinafter described, but before describing the same, I shall proceed to describe the mechanism for actuating the folding mechanism which has just been described. This actuating mechanism is best illustrated in Figs. 1 to 4 inclusive, 8, 21, 25, and 26. The bracket 33 has a substantially square extension 168 which extends laterally outward toward the front side of the machine as clearly illustrated in Figs. 4, 21, 25, and 26. On the forward side 70 of this extension there is secured a bracket 169 which is bolted to the extension by the bolts 170, see Figs. 1 and 4. The bracket 33 has an outwardly and upwardly extending arm 171 and the upper end of this arm has a bearing 172 in which 75

a shaft 173 is rotatably mounted. The shaft 173 also rotates in the bearing 174 on the bracket 33 and the bearing 175 on the bracket 169. The shaft 173 is oscillated by the cam 176 secured to the shaft 67 through the following connections: (see Fig. 3) an arm 177 is pivoted to the shaft 88 and carries an extension 178 having a roller 179 on the end thereof operating within a cam groove 180 in the cam 176. To the shaft 173 is secured an arm 181 and this arm is connected by a link 182 to the end of the arm 177 so that as the arm 177 oscillates, the arm 181 will also oscillate, and as a result, an oscillating movement is imparted to the shaft 173. As will be seen from an inspection of Figs. 4 and 21, the bearings 148 are carried by their respective brackets 183 which in turn are arranged within recessed portions of the sliding blocks 184. This is also shown in Fig. 25.

The shaft 173 does not reciprocate but merely oscillates. A gear segment 187, see particularly Figs. 4, 8, and 21, meshes with the gear 150 and rotates on a bushing 186 which also extends through the bracket 183 to permit the bracket 183 and segment 187 to reciprocate along the shaft 173 while at the same time having rotative movement thereabout. The rotative movement is imparted to the gear segment 187 in the following manner. The gear segment has a tail piece 188, see Figs. 1, 4, and 21. A pin 189 slides freely within a bearing at the end of the tail-piece and this pin in turn is threaded or otherwise secured at the end of the arm 190 which in turn is rigidly secured to the shaft 173 in any well known or desired manner. Therefore as the shaft 173 is oscillating, the pin 189 also oscillates, and as a result, the gear segment is oscillated to rotate the gear 150 for the purposes previously described. At the same time, longitudinal movement of the gear segment along the shaft 173 is permitted because of the sliding connection which the tail-piece 188 has with the pin 189.

The blocks 184 are reciprocated along the guide rod 191 which is supported by the bearings 185 and 192, in which the same is rigidly mounted. The blocks 184 move toward and from each other alternately to bring the folding mechanism into engagement with the opposite extending ends of the tubular wrapper due to the connection between the blocks and the shafts 147 which comprises the brackets 183 rigidly secured to the blocks 184, and also rigidly clamped to the shafts 147. The block 184 at the left in Fig. 21, or Figs. 2 and 4 is reciprocated in the following manner. A link 192 is pivotally connected at 193 to the block and at 194 to an arm 195 pivoted at 196 on a bracket 197 secured to the base frame of the machine. The block 184 at the right is connected by a link 198 pivoted at 199 to the block 184 and to a pivoted arm 200 at 201, which arm in turn is pivoted at 202 to the bracket 197. The arm 200 is rocked about its pivot by the cam 203 shown best in Fig. 3 which has a cam groove therein in which a roller 204 on the end of the tail-piece 205 of the arm 200 travels, and a link 206 connects the arm 200 with a tail-piece 201 on the arm 195 so that the cam 203 rocks the arms 195 and 200 but in opposite directions as will be clear from an inspection of Fig. 2. Thus the blocks 184 are reciprocated simultaneously but in opposite directions by the connections which have just been described, and for the purpose of bringing the folding mechanisms into operative engagement with the tubular ends of the wrapper. While

the blocks reciprocate, the segmental gears are rotated at least for a portion of the reciprocating movement of the blocks. The segmental gears, as previously described, are not oscillated during the entire movement of the blocks 184 toward the tubular wrapper but only during the last part of the folding movement of the folding members so as to twist the folds and arrange the same in overlapping relation with each other.

I shall now describe the manner in which the clutch shifting arms 161 are operated to shift the clutch elements 159. As will be clear from an inspection of Fig. 4, the shaft 162 which carries the clutch shifting arm 161 at the left in Fig. 2 and at the bottom in Fig. 4, to the left of the machine and is mounted to rotate in the bearings 248 which are on the bracket 169. The other shaft 162 is mounted to rotate in the bearings 208 formed as a part of the bracket 33, see Figs. 2, 21, and 26. Each of the shafts 162 has secured thereto an arm 209 located at the left hand side of the machine as viewed in Figs. 1 and 4. These arms 209 are connected by a link 210 pivoted at its ends to each of the arms. The arms 209 extend in opposite directions as will be clear from an inspection of Figs. 21 and 26 so that when one shaft 162 is rotated, the other shaft will also be rotated but in opposite directions. This is for the purpose of shifting the clutch members toward and away from each other simultaneously so that the opposite ends of the tubular wrapper will be operated upon simultaneously. In order to rock the shafts 162, I provide the following mechanism which is perhaps best illustrated in Figs. 2 and 4. In these figures, it will be noted that the clutch shifting arm 161 for operating the clutch at the right in Fig. 2 is provided with an extension 211 which is pivoted to a link 212 extending substantially horizontally. This link is in turn pivotally connected to the upper end of an arm 213 rotatably mounted on the shaft 202 and having a tail-piece 214 which is provided with a roller 215 on the end thereof. This roller 215, see Fig. 3, operates in a suitable cam groove in the cam 216 secured to the shaft 70. Thus as the shaft 70 rotates, the link 212 reciprocates and in turn rocks the clutch shifting elements 161 in such a manner as to operate the fingers 153 on the folding mechanism in the manner which has heretofore been described.

After the folding operation has been completed, the turret carries the container to the next successive position D, where the folds are creased. The creasing mechanism is best illustrated in Figs. 1, 2, 3, 4, 22, and 23, and essentially comprises a pair of disks 217 each of which is carried by its respective shaft 218 rotatably mounted in its bearing 219 and driven by a flexible belt 220 trained over a pulley 221 on the shaft 218 and a pulley 222 on the shaft 223 driven by means of a chain 224 trained over suitable sprockets 225 and 226 on the shafts 223 and 72 respectively. As previously set forth, the chain 65 drives the shaft 72 continuously from the shaft 67 and as a result, the disks rotate continuously in the direction of the arrows shown in Figs. 1 and 3. The bearing members 219 are secured to the reciprocating blocks 184 and the shafts 218 therefore are caused to reciprocate in unison with the blocks 184 to periodically bring the disks 217 against the folds over the ends of the container when the container is at the position D. The shafts 218 are held against longitudi-

nal movement in the bearing members 219 between the hubs of the pulleys 221 and collars 227 secured to the shafts 218. The rotation of the disks 217 is in a counter-clockwise direction as viewed in Fig. 1 as indicated by the arrows on the pulley 222, and it will be noted from an inspection of the folds on the end of the container located at the positions E, F, and G, in Fig. 1 that the overlapping portions thereof extend also in a counter-clockwise direction so that the rotation of the disks does not disturb the overlapping portions but merely creases the folds due to the pressure exerted by the disks against the folds.

15 While the containers are at the position C, there is a tendency for the containers to be rotated while the folds are being produced, and particularly during the time when the fingers are rotating to bring the folds into overlapping relation with each other. It is very important that the containers do not rotate during this operation as the folds will not be properly formed, it being obvious that the rotation of the container at the time the folds are being made would prevent the folds from being brought into overlapping relation. Therefore, I provide a suitable braking mechanism for preventing the rotation of the container at this position, and this mechanism is best illustrated in Figs. 1, 2, 3, 4, 30 and 24. The brake is a simple friction block 228 secured to the end of a lever 229 which is in turn secured to a shaft 230 rotatably mounted in the bearing members 231 which in turn are secured by bolts 232 to the bottom of a horizontally extending bracket 233 secured to the upper side of the bracket 33 as is best illustrated in Figs. 1, 3, 4, 21 and 25. The shaft 230 extends beyond the bearing 231 at the right in Fig. 2 and to the extending portion thereof is secured an arm 234, and this arm is used for rocking the shaft 230 for the purpose of bringing the friction brake 228 into engagement with the wrapped container. The means for rocking the arm 234 is best illustrated in Figs. 2 45 and 3. The end of the shaft 12 carries a rotating disk 235 having a link 236 pivotally connected thereto at 237. The link extends substantially horizontally and has a collar 238 secured to the end thereof. It also has a fixed collar 239 secured thereto and the link itself extends through an opening 240 in the end of the arm 234. The collar 239 is adapted to engage the left hand side of the arm 234 to move it to the right as viewed in Fig. 3 and there is another collar 241 slidably mounted on the link 236 for engaging the other side of the arm 234, the latter being yieldingly pressed against the arm 234 by a spring 242 interposed between the collar 241 and collar 238. As the disk 235 50 rotates, the link is reciprocated and during its travel to the right as viewed in Fig. 3, the arm is rotated with a yielding pressure to bring the friction brake 228 into engagement with the wrapped container, and as soon as the brake 55 engages the wrapped container, the arm 234 stops its rotative movement but there is a further movement of the link 236 which operates to increase the yielding pressure of the friction brake 228 against the wrapped container, since the slide- 60 able collar 241 is stopped by the arm 234 and compresses the spring 242.

5 The container then rotates through the positions E and F to the position G where it is ejected from the turret. The means for ejecting the wrapped containers from the turret is

perhaps best illustrated in Figs. 1 and 2. The ejector 243 is secured to a horizontally extending bar 244 and has the upper end thereof curved somewhat to the shape of the wrapped container and is adapted to reciprocate in a substantially horizontal direction to push the wrapped container out of the pocket located at the position G and move it into the trough 48, the retainer 42 being released during this operation in the manner which has been described previously. 10 The bar 244 is pivotally connected to the upper ends of two arms 245 rotatably mounted on the shafts 246. This gives a parallel motion to the bar 244 and while this motion carries the ejector 243 somewhat in an upward direction as the bar 15 reciprocates, the main movement of the ejector is in a horizontal direction. The ejector 243 extends upwardly between the disks 37 so that it engages the wrapped container substantially centrally thereof. The arms 245 are reciprocated 20 by a link 247 pivotally connected to the side of the cam 55 and to the arm 245 at the right as viewed in Fig. 1.

I shall now briefly describe the operation of the entire machine. The paper 94 is fed onto the table 75 by the feeding member 95 and the containers roll down the chute 93 into a position beneath the table and in alignment with the opening 76 therein. The elevator 77 then moves upwardly to move the container and the paper 25 wrapper 94 into the pocket located at the position A, the wrapper being held in juxtaposition with respect to the container by the prongs 80 extending through the wrapper, and the openings 116 in the manner previously described. 30 After the container and wrapper have been moved into the pocket at the position A, the mechanism shown in Figs. 9, 10, and 11 becomes operative and by means of the folding plate 118 and presser member 130, the end 135 of the wrapper 40 is folded about the container to the position shown in Fig. 10, and as the turret rotates to bring the container to the position B, the upper side of the presser member 142 operates on the glued edge of the wrapper to move the same about 45 the container and to lap the same over the end 135, at the same time pressing the opposed edges of the container against each other to cause the same to adhere to each other to form a tubular wrapper about the container. The spring extension 140 also assists in sealing the overlapping edges to each other as the turret rotates.

When the container with its tubular wrapper arrives at the position C, the folding mechanism becomes operative. The first movement of the 55 folding mechanism brings the fingers 153, see particularly Fig. 12, into a position outside of the extending portion 146 of the tubular wrapper and the fingers 164 on the inside of this same extending portion. The fingers thereafter are caused 60 to move inwardly toward each other by the clutch element 159 which moves to the left to spread the tail-pieces 155 and to move the fingers 153 inwardly between the pins 164. This produces longitudinal folds in the extending portions 146 65 and after these longitudinal folds are formed, the fingers 153 are rotated by means of the oscillating gear segment 187 which meshes with the gear 150 on the shaft 147 which carries the fingers 153. This brings the longitudinal folds 70 into a substantially radial position over the end of the container and in overlapping relation with respect to each other with the result that the folds interlock and are thereafter prevented from unfolding. The turret then rotates to bring the 75

wrapped container into the position D at which position the rotating disks 217 move into engagement with the folds at the end of the container and press the same to crease the folds and thus insure the proper interlocking of the folds and to prevent the folds from moving out of operative position due to the natural resiliencey of the paper when the folds are not creased. The turret then rotates to move the wrapped containers through the positions E and F to the position G where the ejector 243, carried by the bar 244, is moved to the right (in Fig. 1) by the rotating cam 55 and the operative connections between that cam and the reciprocating bar 244. The containers move into the trough 48 and any suitable means may be provided for removing the containers from the trough or the same may be removed by hand. This means, however, is not material to the present invention and is not herein described.

Obviously those skilled in the art to which this invention pertains may make various changes in the construction and arrangement of parts without departing from the spirit of this invention, and therefore I do not wish to be limited except as hereinafter set forth in the appended claims.

Having thus fully described my invention, what I claim as new and desire to obtain by Letters

30 Patent is:

1. In a wrapping machine, the combination with a conveyer for moving a series of articles to wrapping mechanism, of wrapper aligning means located at a position adjacent said mechanism, means for moving said wrapper about an article when the latter arrives at said position, with equal portions thereof protruding beyond opposite ends of said article, means for sealing opposite sides of the wrapper together about the article, and means for folding the extending end portions of said wrapper to substantially entirely enclose said article comprising two sets of fingers at each end of said article, the one set at each end engaging the inner side of the wrapper, and the other set engaging the outer side of the wrapper, means for moving the outer set inwardly toward the inner set to produce folds in said extending portions, means for withdrawing the inner set from the wrapper and means for thereafter moving said folds against the ends of said article.

2. In a wrapping machine, the combination with a conveyer for moving a series of articles to wrapping mechanism, of wrapper aligning means located at a position adjacent said mechanism, means for moving said wrapper about an article when the latter arrives at said position with equal portions thereof protruding beyond opposite ends of said article, means for sealing opposite sides of the wrapper together about the article, and means for folding the extending end portions of said wrapper to substantially entirely enclose said article comprising two sets of fingers at each end of said article, the one set at each end engaging the inner side of the wrapper, and the other set engaging the outer side of the wrapper, means for moving each outer set inwardly toward its corresponding inner set to produce folds in said extending portions, means for moving said sets at one end relative to the sets at the other in a direction at a substantial angle to the said movement of the said outer sets to bring portions of each fold over portions of an adjacent fold on one radial side and another portion of an adjacent fold on the other side, the inner

sets of fingers thereafter being retracted away from said article, and said outer sets continuing their aforesaid movement relative to said inner sets to move said folds flatly against each other and against the ends of said article.

3. A wrapping machine as set forth in claim 2 in which said folds are creased against the ends of said articles by two similar rotating means, each moving toward and against an opposite end of said article and each having a surface substantially co-mating with the adjacent end of said article whereby the folds are pressed firmly against the end of said article and creased to hold the same in position.

4. Means for folding the open cylindrical end 15 of a wrapper over the end of an article comprising a circular inner row of fingers and a circular outer row of fingers, means for moving said rows respectively against the inner and outer surfaces of said extending portion and relatively toward each other to produce longitudinal folds, means for rotating said rows to bring a portion of each fold under an adjacent fold on one side thereof and over an adjacent fold on the other side thereof and means to retract said inner row while 25 leaving the outer row in engagement with the wrapper.

5. Means for folding the open cylindrical end of a wrapper over the end of an article comprising a circular inner row of fingers and a circular 30 outer row of fingers, means for moving said rows respectively against the inner and outer surfaces of said extending portion and relatively toward each other to produce longitudinal folds, means for rotating said rows to bring a portion of each 35 fold under an adjacent fold on one side thereof and over an adjacent fold on the other side thereof, means to retract said inner row while leaving the outer row in engagement with the wrapper and means for thereafter pressing the overlapping 40 folds inwardly until the folds are substantially in a single plane and extending substantially radially.

6. A device as set forth in claim 5 in which a means subsequently engages said folds and 45 creases the same.

7. A device as set forth in claim 5 in which a means subsequently engages said folds and rotates while in wiping contact therewith to press the folds together and crease the same.

8. A device as set forth in claim 5 in which all the folds overlap in the same direction and in which a means is provided for engaging all of the folds simultaneously to crease the same, and in which said last mentioned means rotates while 55 in engagement with said folds in the direction in which the overlapping portions of said folds extend.

9. A wrapping machine comprising an article conveyer having pockets, means for moving a 60 series of wrappers into a predetermined position adjacent the path of travel of said pockets and opposite to the open sides of said pockets when at said position, means for applying glue to said wrapper along one edge thereof as said wrapper moves to said position, means for feeding an article to a position adjacent said wrapper on the side thereof opposite the side on which said conveyer moves, and for simultaneously moving said article against said wrapper into said pocket 65 and for restraining each wrapper to move along a predetermined fixed path during this operation, whereby the same is always properly positioned with respect to said article and pocket when said article is moved fully into said pocket, and where- 70

by the wrapper is always in the proper position for the subsequent folding operation, means for moving the glued edge of said wrapper into overlapping engagement with the opposite edge of said wrapper with the glue lying between said overlapping edges after said article is moved into said pocket to form a tubular container with the opposite ends thereof protruding beyond the ends of the article, and means for producing longitudinal folds in said extending portions and for folding the same in overlapping relation with respect to each other against the end of said article.

10. A wrapping machine comprising an article conveyer having pockets, means for moving a series of wrappers into a predetermined position adjacent the path of travel of said pockets and opposite to the open sides of said pockets when at said position, means for applying glue to 15 said wrapper along one edge thereof as said wrapper moves to said position, means for feeding an article to a position adjacent said wrapper on the side thereof opposite the side on which said conveyer moves, and for simultaneously moving said article against said wrapper into said pocket while restraining each wrapper to move along a predetermined fixed path during this 20 operation whereby the same is always properly positioned with respect to said article and pocket 25 when said article is moved fully into said pocket, and whereby the wrapper is always in the proper position for the subsequent folding operation, and means for moving the glued edge of said wrapper into overlapping engagement with the opposite 30 edge of said wrapper with the glue lying between said overlapping edges after said article is moved into said pocket, comprising two sets of fingers at each end of said article, the one set at each end engaging the inner side of the wrapper, and the other set engaging the outer side 35 of the wrapper, means for moving the outer set inwardly toward the inner set to produce folds in said extending portions, and means for thereafter moving said folds against the ends of said article.

45. 11. A wrapping machine comprising an article conveyer having pockets, means for moving a series of wrappers into a predetermined position adjacent the path of travel of said pockets and opposite to the open sides of said pockets when at said position, means for applying glue to said wrapper along one edge thereof as said wrapper moves to said position, means for feeding an article to a position adjacent said wrapper on the side thereof opposite the side on which said conveyer moves, and for simultaneously moving said article against said wrapper into said pocket while restraining each wrapper to move along a predetermined fixed path during this 50 operation whereby the same is always properly positioned with respect to said article and pocket when said article is moved fully into said pocket, and whereby the wrapper is always in the proper position for the subsequent folding operation, and means for moving the glued edge of said wrapper into overlapping engagement with the opposite edge of said wrapper with the glue lying between said overlapping edges after said article is moved into said pocket, comprising two sets of fingers at each end of said article, the one set at each end engaging the inner side of the wrapper, and the other set engaging the outer side of the wrapper, means for moving the outer set inwardly toward the inner set to produce folds in said extending portions, means for

50 moving said sets relative to each other in a direction at a substantial angle to the said movement of said outer set to bring portions of each fold over portions of an adjacent fold on one side and under an adjacent fold on the other, means for moving all of said folds against the ends of said article, and means for creasing the folds to prevent the unfolding thereof and to hold the same in overlapping relation with each other.

12. Means for closing the open tubular end of a wrapper comprising a plurality of fingers extending substantially parallel to the axis of said open end but movable inwardly toward each other and longitudinally of said axis, of means for moving said fingers toward said wrapper and then inwardly against the outer surface thereof to fold portions thereof inwardly, a plurality of additional means engaging the inner surface of said tubular portion and staggered peripherally with respect to said fingers to resist more than a predetermined amount of inward movement of the portions of said wrapper intermediate said portions engaged by said fingers until said folds have been substantially made, means for withdrawing said additional means and means for rotating said fingers with the additional means withdrawn to move said folded portions into overlapping relation with each other and into a plane substantially perpendicular to said axis.

30 13. In a wrapping machine, means for engaging an article with a wrapper, means for moving the wrapper about the article, means operable as the wrapper engages the article and while the wrapper is being moved about the article for holding a portion of the wrapper in fixed position with respect to the article, said holding means having provisions for perforating the wrapper to positively hold it in position.

40 14. In a wrapping machine, means for engaging an article with a wrapper, means for moving the wrapper about the article and for moving the wrapper and article as a unit, and means cooperable with the article moving means operable as the wrapper engages the article for holding a portion of the wrapper in fixed position with respect to the article as the wrapper and article are moved, said holding means having provisions for perforating the wrapper and having independent actuating means but being movably connected with its actuating means so that it conforms to variations in the movement of the article.

45 15. In a wrapping machine, a movable conveyor for an article, means for moving a wrapper about the article comprising a member engageable with the wrapper and movable thereafter into position adjacent the article, said member being resiliently urged against the article to maintain a fixed position with respect thereto and to maintain the wrapper in position thereon as the article moves with the conveyor.

55 16. In a wrapping machine, a movable conveyor for an article and wrapper, means for moving the wrapper about the article comprising a member engageable with the wrapper and movable thereafter into position adjacent the article, said member being resiliently urged against the article to maintain a fixed position with respect thereto and to maintain the wrapper in position thereon as the article moves on a conveyor, and a member engaged by the article and wrapper as the conveyor moves for wrapping another end of the wrapper about the article, said latter member being independently and resiliently mounted to follow

and conform to the configuration of the article as the article is moved.

17. In a wrapping machine, means for folding a wrapper comprising a plurality of fingers radially arranged around a central support member, and means for moving each finger toward the axis of the support member in a plane passing near but not through the axis of the support member.

18. In a folding mechanism, means for folding a wrapper comprising a support rotatable about an axis and movable axially toward and away from the wrapper, folding members mounted on said support for movement relative thereto in a direction radially inward toward the axis of the support and away from the wrapper.

19. In a folding mechanism, means for folding a wrapper comprising two sets of rigid circumferentially arranged members for engaging the inner and outer surfaces respectively of the wrapper, said sets of members being relatively movable radially and axially.

20. In a folding mechanism, means for folding a wrapper comprising a set of circumferentially disposed pivotal wrapper engaging members, resilient means circumferentially encircling said members to yieldingly urge them in one direction, and cam means for moving the members in opposition to said resilient means.

21. In a folding mechanism, means for folding a wrapper comprising two sets of circumferentially arranged members for engaging the inner and outer surfaces respectively of the wrapper, and a single cam member for simultaneously moving said sets of members relatively radially and axially.

22. In a folding mechanism, means for folding a wrapper comprising two sets of circumferentially disposed wrapper engaging members, a support upon which one set of members is pivoted and through which the other set is axially movable.

23. In a folding mechanism, means for creasing the folded portions of a wrapper comprising a rotatable disk engageable with the folded portions, and means to apply a yieldingly increasing pressure to the disk against the folded portions.

24. In a folding machine, means for folding a wrapper comprising two sets of circumferentially arranged members, said members being relatively axially and radially movable, means for bringing the sets of members into operative position for engagement with the inner and outer surfaces respectively of the wrapper, and means for moving one set of members axially and the other set radially while the members are in operative position.

25. In a folding machine, means for folding a wrapper comprising two sets of circumferentially arranged members, said members being relatively axially and radially movable, means for bringing the sets of members into operative

position for engagement with the inner and outer surfaces respectively of the wrapper, and means for moving one set of members axially and the other set radially while the members are in operative position, said moving means comprising a cam to which the one set of members is secured and with which the other set is engageable.

26. In a folding machine, means for folding a wrapper comprising outer and inner sets of members circumferentially arranged about an axis and engageable respectively with the outer and inner surfaces of the wrapper, and means for moving each member of said outer set of members toward said axis in a plane passing near but not through the axis.

27. In a wrapping machine, means for folding a tubular wrapper end into a plurality of radial overlapping folds comprising a plurality of circumferentially arranged folding fingers, and means for moving said fingers toward and away from the wrapper axis along lines of movement uniformly displaced from true radial lines.

28. In a wrapping machine, means for folding a tubular wrapping end into a plurality of radial overlapping folds comprising a plurality of circumferentially arranged folding fingers, and means for moving said fingers along generally radial lines with respect to the wrapper axis but deviating therefrom at the axis of the wrapper whereby to arrange the folds with a portion of the inner end edge of each fold under an adjacent fold.

29. In a folding mechanism, means for folding a tubular wrapper end comprising a support rotatable about the wrapper axis and movable axially toward and away from the wrapper end, and circumferentially arranged folding members pivotally mounted on said support for movement thereon relative thereto in a direction radially inward toward the axis of the wrapper and away from the wrapper end.

30. In a folding mechanism, means for folding a tubular wrapper end comprising two sets of circumferentially arranged relatively radially movable members for engaging the inner and outer surfaces respectively of the wrapper, and means for supporting each of said sets of members, said support means being relatively movable axially.

31. In a folding machine, means for folding a wrapper comprising two sets of circumferentially arranged members, said members being relatively axially and radially movable, means for bringing the sets of members into an operative position for engagement with the inner and outer surfaces respectively of the wrapper, and means for moving one set of members axially and the other set radially in predetermined timed relation while the members are in operative position.
